CLAIM

The ornamental design for a pump support bracket for a jettied whirlpool bath, as shown and described.

DESCRIPTION

FIG. 1 is an isometric view of a pump support bracket for a jettied whirlpool bath showing my new design; FIG. 2 is a top plan view thereof; FIG. 3 is an elevational view of one end; FIG. 4 is an elevational view of the opposite end; FIG. 5 is an elevational view of one side, and the view of the side opposite is a mirror image thereof; and FIG. 6 is a bottom plan view.

FIG. 1

FIG. 2

FIG. 3

FIG. 4

FIG. 5

FIG. 6
